(57) **CLAIM**

The ornamental design for a light holder for gun scope, as shown and described.

DESCRIPTION

FIG. 1 is a perspective view of a light holder for gun scope showing my new design;

FIG. 2 is a front view of a light holder for gun scope shown in FIG. 1;

FIG. 3 is a back view of a light holder for gun scope shown in FIG. 1;

FIG. 4 is a right side view of a light holder for gun scope shown in FIG. 1;

FIG. 5 is a left side view of a light holder for gun scope shown in FIG. 1;

FIG. 6 is a top view of a light holder for gun scope shown in FIG. 1;

FIG. 7 is a bottom view of a light holder for gun scope shown in FIG. 1; and,

FIG. 8 is a perspective environmental view of a light holder for gun scope shown in FIG. 1 employed on a gun scope. The subject matter shown within the broken lines in FIG. 8 forms no part of the specified embodiment.
